UNITED STATES PATENT OFFICE.

ANNA L. STEIG, OF CHURCHS FERRY, NORTH DAKOTA.

CLOTHES-HANGER.

1,214,606.

Specification of Letters Patent.

Patented Feb. 6, 1917.

Application filed September 4, 1915. Serial No. 48,951.

To all whom it may concern:

Be it known that I, ANNA L. STEIG, a citizen of the United States, residing at Churchs Ferry, in the county of Ramsey and State of North Dakota, have invented or discovered certain new and useful Improvements in Clothes-Hangers, of which the following is a specification, reference being had therein to the accompanying drawing.

- 10 This invention has for its object to provide a clothes hanger which is adapted to hold different articles of clothing, which may be made with comparatively little expense and which will be convenient in use.
- 15 To this end the improved clothes hanger comprises a series of bow-springs between which the articles to be suspended are inserted, the holding bow-springs being preferably thin, flat strips of steel suitably 20 mounted in a holder, all as will hereinafter more fully appear.

In the accompanying drawing Figure 1 is a plan view, partly broken away, of the improved clothes hanger, and Fig. 2 an end view thereof.

Referring to the drawing 12 denotes a back-board preferably having a mortise 13 adapted to receive a U-shaped strip of metal 14, the end arms of which embrace 30 the open ends of a series of bow-springs 15 held apart at their said open ends by a series of wooden blocks 16 herein shown as being attached to the back or main part of the said U-shaped metal strip by screws 17.

35 To the back-board 12 are attached, by screws 18, wooden housing and bracing strips 19 which serve to cover the blocks 16 and to brace the bow-springs 15 vertically, the said strips 19 being arranged above and 40 below the said bow-springs 15 in front of the said blocks 16, and coöperating with the metal strip 14 to connect the said bow-springs and blocks to the back-board 12.

A rod 21 passes through the arms of the 45 U-shaped strip 14 and also through all of the bow-springs 15 and blocks 16, said rod being preferably upset or riveted at its ends

outside of the said arms so as to secure all the said parts, through which it passes, together. 50

The back-board 12 is, in the present instance, provided with holes 22 for the reception of screws by which it may be rigidly secured to any suitable vertical support, but it may be otherwise fixed in a proper working position. 55

In the use of the improved clothes hanger the articles to be held will be inserted between the bow-springs 15 by being forced inward from the outer rounded ends of said 60 bow-springs, as will be readily understood.

The improved clothes hanger may comprise any suitable desired number of bow-springs 15 which may be of any desired size or length and may be of any suitable flat 65 spring metal, as steel or brass. The bow-springs, being formed of flat strips of metal, will particularly adapt the holder for suspending men's pantaloons which will be held creased when suspended by their bottom ends in the holder. 70

Having thus described my invention I claim and desire to secure by Letters Patent.

A clothes hanger comprising the combination with a back-board having a mortise, of 75 a U-shaped metal strip the body of which is arranged in said mortise and which strip is attached to said back-board, a series of bow-springs within the arms of said metal strip, 80 a series of blocks within the open ends of said bow-springs, said blocks being attached to said back-board, wooden housing and bracing strips also secured to said back-board and disposed above and below the 85 inner ends of said bow-springs, and a rod passing through said blocks and the inner ends of said bow-springs and also through the arms of said U-shaped strip, the ends of said rod being riveted to said arms to secure 90 said blocks, bow-springs and arms together.

In testimony whereof I affix my signature.

ANNA L. STEIG.
